UNITED STATES PATENT OFFICE.

ELMER C. PITCHER AND FRED W. SCHMITZ, OF SAN FRANCISCO, CALIFORNIA.

TANK.

Application filed July 18, 1923. Serial No. 652,289.

To all whom it may concern:

Be it known that we, ELMER C. PITCHER and FRED W. SCHMITZ, citizens of the United States, and residents of the city and county 5 of San Francisco, State of California, have made a new and useful invention—to wit, Improvements in Tanks; and we do hereby declare the following to be a full, clear, concise, and exact description of the same.

10 This invention relates particularly to an improved construction of wooden receptacles for the storage of fluids.

The principal object of this invention relates to the construction of a wooden 15 tank having joints between the staves of the sides and bottom of the tank maintained in a moistened condition to swell the wood and prevent shrinkage when the fluid content is drained from the tank, or when filled.

20 A further object of the invention is to provide a wooden tank having the stave joints in the sides and bottom of the tank communicating one with the other so that a continuous circulation may be maintained 25 throughout the stave joints in the sides and bottom of the tank through an inlet and outlet.

A still further object of our invention is to provide an apparatus that will be superior 30 in point of simplicity, inexpensiveness of construction, positiveness of operation and facility and convenience in use and general efficiency. Other objects and advantages will appear as this description progresses.

35 In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

40 In the accompanying one sheet of drawings,

Fig. 1 represents a perspective view of a tank constructed in accordance with my invention.

45 Fig. 2 is a section taken through Fig. 1 on the line 2—2.

Fig. 3 is perspective view of a single stave.

50 Fig. 4 is a form of tank bottom having a modified fluid course around the bottom thereof.

In detail, the construction illustrated in the drawings comprises a conventional type of wooden fluid tank formed of a plurality of side staves 1, each of which has a croze 2 adjacent the lower end thereof, into which the bottom members or staves 3 are adapted to pass. The sides and bottom of the tank are assembled and hooped by the adjustable metal bands 4 around the outside thereof in a conventional manner. The abutting or matching faces of each pair of staves, are provided with complementary grooves or slots 5 therein, arranged between the inner and outer faces of said staves and extending from a point adjacent the upper end of the stave down to a groove or passage 6 adjacent the croze 2, said passage extending entirely through the stave to communicate the bottom ends of the grooves 5. 75 Each stave near the upper end is provided with a hole or passage 7 extending between and connecting the grooves 5 on the opposite sides of each stave. Thus, when the tank is assembled the passages and holes 6 and 7 in the top and bottom of the side staves 1 will form a continuous and uninterrupted passage entirely around the tank.

The opposite side edges of each of the bottom members or staves 3 are provided with corresponding grooves or slots 8, extending the entire length of the stave and matching with the grooves in adjacent staves. The edges of the bottom members, fitted within the croze 2, are grooved as at 9 to provide a continuous and connected duct around the outer edge of said bottom within the croze. Connecting passages 10 are bored through the bottom of the staves to communicate the bottom grooves 6 with the continuous groove 9 in the tank bottom. After the tank is assembled, all of the grooves in the stave joints in the sides and bottom communicate with each other to form conduits, through which a fluid may 100 be circulated.

In the practice of this invention, water would be admitted through the inlet 11 into the bottom passage 6 of the side staves 1, from whence it would circulate through the connecting passage 10 into the continuous groove 9 in the bottom, around the croze joint and from which fluid would be introduced through the passages 8 into the bottom stave joints 3. The grooves 5 in the joints of the side staves 1 would communicate the water circulation at the upper end

with the continuous passage 9 and be drawn through the outlet 12. Water would be circulated throughout every stave joint in either the side or bottom of the assembled 5 tank to swell the respective joints substantially leak proof, to prevent contraction or shrinkage between the stave joints at all times, either when the tank would be filled with fluids, or other solutions, or when 10 empty.

The modified form of tank bottom shown in Fig. 4 is constructed slightly different from that previously shown and described. The opposite side edges of each of the bottom 15 staves 3 are provided with the corresponding grooves 8 throughout approximately the entire length. The grooves do not extend into the croze 2 nor are the ends of the bottom staves, fitted within the croze, 20 provided with a groove 9. Each bottom stave is provided with a hole or passage 13, extending entirely through, between grooves 8, from one edge to the other, the hole in one stave being at the end thereof opposite the 25 holes in the adjacent stave, so that the said passages are placed at the same ends of alternate staves. An inlet passage 14 would be provided in the croze to communicate the groove 8 of a bottom stave joint with the 30 bottom groove 5 of the side staves, whereby the water or other circulating medium would wind a tortuous passage throughout the lengths of and across the widths of each individual bottom stave so as to escape 35 through the outlet 15 to the atmosphere. Either the modified or preferred forms of construction serve to keep the stave joints in the desired moistened condition and to thus prevent leakage.

40 Experiments with the form of invention described have proven it a good design for holding solutions which would rapidly work through the stave joints of tanks constructed by any of the older known methods. Tanks 45 of this character may be efficiently used for the storage of oil, which generally has a tendency to shrink the wooden tank staves, necessitating the continual tightening up of the hoops, however, this shrinkage is eliminated where the stave joints are thoroughly saturated with water according to the practice of my invention.

50 Having thus described this invention, what we claim and desire to secure by Letters 55 Patent is:—

1. A tank consisting of a side wall and bottom, composed of staves and having grooves in the joints of said staves; and spaced passages in the opposite ends of each of said side wall staves communicating with 60 said bottom grooves.

2. A tank composed of staves having water passages in each of the stave joints; and a stave bottom in said tank having water passages in each of the stave joints and connecting with said first mentioned passages.

3. A tank composed of staves having water passages in each of the stave joints; a conduit in each of said staves connecting the passages on opposite sides thereof; and a 70 stave bottom in said tank having water passages in each of the stave joints and connecting with said first mentioned passages.

4. A tank composed of staves having water passages in each of the stave joints; independent conduits in the opposite ends of each of said staves connecting the passages on opposite sides thereof; and a stave bottom in said tank having water passages in each of the stave joints and connecting with 80 said first mentioned passages.

5. A tank composed of staves having water passages in each of the stave joints; a conduit in each of said staves connecting the water passages on opposite sides thereof; a 85 stave bottom in said tank having water passages in each of the stave joints connected with said first mentioned water passages to form a continuous water passage throughout the tank and bottom staves.

6. A tank composed of staves having water passages in each of the stave joints; a conduit in each of said staves connecting the water passages on opposite sides thereof; a stave bottom in said tank having water 95 passages in each of the stave joints; and conduits connecting the water passages in adjoining staves, arranged at the same ends of alternate staves and connected with said first mentioned water passages to 100 form a continuous water passage through the tank and bottom staves.

In testimony whereof, we have hereunto set our hands at San Francisco, California, this 26th day of October 1922.

ELMER C. PITCHER.
FRED W. SCHMITZ.

In presence of—

LINCOLN V. JOHNSON.
